(57) **CLAIM**

An ornamental design for a fire extinguisher with valve, as
shown and described.

DESCRIPTION

FIG. 1 is a top perspective view of a first embodiment of a
fire extinguisher with valve;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a bottom perspective view thereof;

FIG. 9 is a section view taken along the reference line 9-9
of FIG. 5;

FIG. 10 is a top perspective view of a second embodiment
of the fire extinguisher with valve;

FIG. 11 is a front view thereof;

FIG. 12 is a back view thereof;

FIG. 13 is a left side view thereof;

FIG. 14 is a right side view thereof;

FIG. 15 is a top view thereof;

FIG. 16 is a bottom view thereof;

FIG. 17 is a bottom perspective view thereof;

FIG. 18 is a section view taken along the reference line
18-18 of FIG. 14; and,

FIG. 19 is a section view taken along the reference line
18-18 of FIG. 14 with a hose coupler being shown in a
second position.

The portions depicted in broken lines form no part of the
claimed design.
